UNITED STATES PATENT OFFICE

154,136

DESIGN FOR A COMBINED FLOWER
STAND AND TRELLIS

Thomas S. Morris, Birmingham, Ala.

Application March 3, 1947, Serial No. 137,291

Term of patent 3½ years

(Cl. D35—3)

To all whom it may concern:

Be it known that I, Thomas S. Morris, residing at Birmingham, in the county of Jefferson and State of Alabama, have invented a new, original, and ornamental Design for a Combined Flower Stand and Trellis, of which the following is a specification, reference being had to the accompanying drawing, forming part thereof, in which

Fig. 1 is a front elevational view showing my new design of a combined flower stand and trellis;

Fig. 2 is a top plan view; and

Fig. 3 is an end view.

I claim:

The ornamental design for a combined flower stand and trellis, substantially as shown.

THOMAS S. MORRIS.
